(57) **CLAIM**

The ornamental design for a wireless portable battery for a mobile device, as shown and described.

DESCRIPTION

FIG. 1 illustrates a perspective view of a wireless portable battery for a mobile device;

FIG. 2 illustrates a front side of the wireless portable battery for a mobile device;

FIG. 3 illustrates a rear side of the wireless portable battery for a mobile device;

FIG. 4 illustrates a left side of the wireless portable battery for a mobile device;

FIG. 5 illustrates a right side of the wireless portable battery for a mobile device;

FIG. 6 illustrates a top side of the wireless portable battery for a mobile device;

FIG. 7 illustrates a bottom side of the wireless portable battery for a mobile device; and,

FIG. 8 illustrates another perspective view of the wireless portable battery for a mobile device.

1 Claim, 7 Drawing Sheets
